UNITED STATES PATENT OFFICE.

JAMES R. MCKAMEY AND ROBERT N. MCKAMEY, OF ASHLAND, OREGON.

BUTT HOOK.

Application filed March 15, 1924. Serial No. 699,605.

To all whom it may concern:

Be it known that we, JAMES R. MCKAMEY and ROBERT N. MCKAMEY, citizens of the United States, residing at Ashland, in the 5 county of Jackson and State of Oregon, have invented new and useful Improvements in Butt Hooks, of which the following is a specification.

Our present invention has reference to 10 hooks employed by loggers and commonly known as butt hooks, and our object is to simplify and improve the existing art by producing a device for this purpose characteristic of simplicity in construction, coupled with great strength and durability and 15 which is retained in locked condition by the strain thereon.

With the above broadly stated objects in view and others which will appear as the 20 nature of the invention is better understood, reference is to be had to the drawing which accompanies and which forms part of this application.

In the drawing:—

25 Figure 1 is a plan view of the improvement.

Figure 2 is a similar view with one of the plates constituting the frame removed.

Figure 3 is a vertical section on the line 30 3—3 of Figure 2.

As disclosed by the drawing, our improved butt hook comprises a frame or body made up of two removably connected sections, each of which being similar and the same as 35 a whole being indicated by the numeral 1. The body sections are secured together by bolts which are engaged by nuts and these nuts are let in depressions in one of the body plates.

40 The body has its outer or hook carrying end widened and its sides gradually inclined to its opposite end. This last mentioned inner end is centrally formed with a boss-like extension which has a bore therethrough that 45 communicates with a passage 2 in the body. The side walls of the passage 2 are flared away from each other to the outer or hook carrying end of the body. Passing through the boss and entering the referred to passage, and babbitted or otherwise effectively 50 secured therein there is the cable 3.

The hook carrying end of the body 1 is centrally depressed and the wall of the said depression is curved or of arcuate formation, as indicated by the numeral 4. The 55 passage 2 communicates with the notched

portion 4, and at its point of communication therewith is rounded toward the sides of the body, as indicated by the numeral 5.

For distinction, the notched portion of 60 the body will be referred to as the mouth thereof. The body, inward of its mouth has its sides provided with crescent-shaped openings in which are received the reduced ends 5' of what I will term a bolt member 6, the body of the bolt member being crescent-shaped in cross section and its concaved portion is arranged in a line with the concaved mouth of the body. Loosely arranged over the inner rounded portion of the bolt 6 there 65 is the ring-like body 8 of the hook. The beak of the hook is indicated for distinction by the numeral 9, and the split ring constituting the body thereof has its outer edge 70 corrugated or formed with teeth, as indicated by the numeral 10. These teeth are in mesh with similar teeth on a roller 11, the shaft 12 of which being journaled in suitable 75 bearing openings in the members constituting the body.

The split ring body of the hook is loosely arranged on the bolt and when the hook is swung to closed and gripping position the toothed edge of the body will contact with one of the rounded walls 5 of the passage 2, 80 the said toothed portion being likewise engaged by the toothed roller 11. The roller 11 provides a bracing or reinforcing means for the hook. The strain on the hook will prevent the accidental opening thereof, and 85 from the foregoing description when taken in connection with the drawing it is believed that the construction and advantages of our device will be apparent to those skilled in the art to which such inventions relate.

90 Having described the invention, we 95 claim:—

1. In a device for the purpose set forth, 100 a body having a passage therethrough and a concaved mouth at one end thereof, a crescent-shaped bolt in the body of the said mouth thereof, a split ring having one of its ends formed with a hook loosely arranged around the bolt, said ring having its outer edge toothed, and a toothed roller revolvable in 105 the body meshing with the teeth of the ring.

2. In a device for the purpose set forth, a body having a passage therethrough and a concaved mouth at one end thereof, a cable 110 secured in the body and projecting through the second end thereof, a crescent-shaped bolt secured in the passage of the body at

the mouth thereof, said passage having its walls rounded at points opposite the bolt, a split ring member having one end merging into a hook loosely arranged over the bolt, 5 said ring member having its outer edge toothed, and a toothed roller journaled in the passage of the body to the rear of the

ring member and meshing therewith, all as and for the purpose set forth.

In testimony whereof we affix our signatures.

JAMES R. McKAMEY.
ROBERT N. McKAMEY.
